DESIGN FOR A KITCHEN CABINET

Norma A. Tod, Los Angeles, Calif.

Application October 12, 1936, Serial No. 65,265

Term of patent 14 years

To all whom it may concern:

Be it known that I, Norma A. Tod, a citizen of the United States, residing at Los Angeles, in the county of Los Angeles and State of California, have invented a new, original, and ornamental Design for a Kitchen Cabinet, of which the following is a specification, reference being had to the accompanying drawing, forming a part thereof:

I claim:

The ornamental design for a kitchen cabinet, as shown.

NORMA A. TOD.
